as shown and described.**DESCRIPTION**

FIG. 1 is a perspective view of the sawblade extension fitting showing my new design;

FIG. 2 is a rear elevational view thereof;

FIG. 3 is a right side elevational view thereof;

FIG. 4 is a left side elevational view thereof;

FIG. 5 is a front elevational view thereof;

FIG. 6 is a bottom plan view thereof; and,

FIG. 7 is a top plan view thereof.

The broken line showing of the saw blade is for illustrative purposes only and forms no part of the claimed design.
